(57) **CLAIM**

The ornamental design for a socket-strip, as shown.

DESCRIPTION

FIG. 1 is a perspective view of a socket-strip showing my new design.

FIG. 2 is a top plan view thereof.

FIG. 3 is a right side elevational view thereof, the left side being a mirror image.

FIG. 4 is a bottom plan view thereof; and,

FIG. 5 is a front elevational view thereof.

The rear of the socket-strip is flat and unornamented.
